(57) **CLAIM**

The ornamental design for flash drive, as shown and described.

DESCRIPTION

FIG. 1 is a perspective view of flash drive showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view in use thereof; and,

FIG. 9 is another perspective view in use

The portions shown in dashed lines do not form part of the design.

1 Claim, 6 Drawing Sheets
